CHARLES P. TOLMAN, OF KEW GARDENS, NEW YORK, ASSIGNOR TO PETROLEUM CONVERSION CORPORATION, OF NEW YORK, N. Y., A CORPORATION OF DELAWARE

METHOD OF AND APPARATUS FOR HEATING AND MINGLING FLUIDS

Application filed January 3, 1927. Serial No. 158,723.

My present invention relates to the heating of fluids by mingling therewith other and heated fluids, the object of the invention being to provide a method and apparatus for such purpose wherein the fluid to be heated may receive the desired heat content within a minimum temperature gradient or range and within a minimum time interval.

To this end I have provided in the embodiment herein disclosed means in the form of an injector for admitting the heating fluid into contact with the fluid to be heated, a stream of the mixed fluids under relatively high velocity thereby being created. In this manner a maximum surface of contact is formed between heating and heated fluids, which, however, in itself would not be adequate for the purpose since temperature is immediately lost by expansion. Accordingly I then add additional quantities of the heating fluid by means of other and auxiliary injectors or jets placed in the path of this moving stream, the arrangement being such that these newly injected streams of heating fluids not only compensate for the heat lost by expansion or by other causes (as for example an endothermic reaction undergone by the fluid being heated) but add to the velocity of the moving stream. This augmented velocity I also preferably utilize to draw thereinto additional quantities of the fluids to be heated, suitable injector means being employed for this purpose. This action may be repeated any desired number of times, at least one auxiliary heating jet being provided for each expansion and drawing in of additional fluid to be heated.

My invention is susceptible of varied applications, but it is particularly adapted to the cracking of oils by the treatment and mingling therewith of a heated fluid, such as hydrocarbon gases of appropriate composition, steam, mercury vapor, etc., or mixtures thereof, and is herein described as applied to such use although it is to be understood that the invention is not to be limited thereto.

In the cracking of petroleum it is of very great importance that the heat transfer take place within a narrow range of temperatures; otherwise, if the temperature gradient

be too great, either part of the oil will be destroyed through overheating or else the average temperature imparted thereto may be too low. Due to the rapidity of the cracking reaction and to the increased volume of the products formed, it is usually not feasible to increase the time factor, which would permit of small temperature gradients to be employed. Moreover, cracking of oil is an endothermic reaction, the supplying of the additional heat for which is admirably taken care of by the described apparatus. Furthermore, it is now recognized that the reaction of cracking is more or less independent of the pressure, so that this factor need no longer be given prime consideration.

By the operation of my invention the vapor of the hydrocarbon to be cracked will be so intimately mixed with the hot fluid supplying the heat for such cracking that substantially all of such vapor will be brought to the temperature at which it is desired to crack, within a space of time less than the reaction time, thereby preventing the formation of cracked products corresponding to temperatures lower than the desired cracking temperature. If the petroleum is not so heated, there would be formed as its temperature rose, cracked products or fractions corresponding to the various temperatures through which the petroleum passes while reaching the maximum, and such fractions once formed would largely resist or be refractory to further cracking and so persist in the final mixture.

In the annexed drawing:—

The figure shows an illustrative embodiment of the invention applied to the cracking of hydrocarbon oils.

Referring now to the drawing by characters 90 of reference 10 denotes a heating element, as for example a blast stove, connected with a stack 11, for supplying heated fluid to the reaction or conversion chamber 12. The latter, to which the invention is particularly directed, consists of a chamber having therein a plurality of nozzles 13, 14, and 15 of venturi shape and of increasing size. The heating fluid is introduced through a primary nozzle 17, behind the flared portion of the 100

first nozzle 13, so as to form therewith an injector. Nozzle 14 occupies a position relative to nozzle 13 as does nozzle 13 with respect to primary nozzle 17. A third nozzle 15, 5 larger than the two described, is disposed to receive the products from injector 14 in similar manner. Primary nozzle 17 is supplied with the heated fluid by means of a pipe 19 leading from the hot stove 10 or other source 10 of heat. Preferably also communicating with the same source is a pipe 21 which supplies the heating fluid to auxiliary nozzles 13a and 14a. Suitable valves d and e are 15 respectively provided in these pipes leading thereto.

Preferably I preliminarily vaporize the oil undergoing cracking and introduce the same in the form of vapor into the conversion chamber. My invention also contemplates 20 the treatment of oil in the liquid state, but I prefer using the oil in the vapor state, as by so doing a much more intimate mixture of oil and gas is possible. Accordingly I provide an evaporator 23 of conventional type and 25 admit the produced vapors into the conversion chamber by means of a pipe 24. Oil is fed into the heater by means of a pipe 25. Evaporation of the oil may be facilitated by the use of steam or neutral gases introduced 30 thru pipe 26 as is known in the art. It is not contemplated that the conditions prevailing within the evaporator 23 will produce any substantial amount of cracking of the oil therein.

35 The products leaving the conversion chamber pass through a conduit 27 into a condenser 28 where the desired products are separated. If desired various heat exchange apparatus may be employed to utilize the heat in the 40 outgoing products from the conversion chamber, as is known in the art. The gaseous products are collected in a holder 30. The condensed substances from condenser 28 containing the desired products of the system are 45 collected in the receiver 31.

It will be understood that the preferred 50 means for heating the heat carrying gases consists in a suitable number of blast stoves of conventional type, although of course my invention is not necessarily limited to this 55 particular mode of heating the gases. In the operation of the apparatus shown, a stove is suitably brought up to temperature by blasting in the usual manner, i. e. by means of oil or producer gas, etc., after which the 60 gases to constitute the heat carrier are led therethrough by a pipe not shown and hence through the pipe 19 to the conversion chamber. As previously stated the invention does 65 not depend upon any specific type of carrier gas, this being determined by the facility of heating such gases and by the specific effect desired upon the oil. Thus I may use steam entirely; or the lighter hydrocarbon gases which, after severe heating yield large quan-

tities of hydrogen; or mixtures of steam and these gases; or other gases of an entirely neutral character such as nitrogen; or I may use mercury vapor which, however, would require a different form of superheater. Furthermore my invention permits treatment of the oil or other substance by different fluid media during the process. As shown nozzles 13a and 14a may be fed by pipes 13b and 14b respectively and thus independently of vapor pipe 19. For this purpose, appropriate valves are provided as shown. In this manner, the oil vapor may be successively subjected to the action of hot hydrocarbon gas, mercury vapor or steam if such is desired. In 80 addition, valve 19a in pipe 19 and pipe 19b leading thereto allow of feeding a hot fluid into the conversion chamber 12 from a different source.

Accordingly various changes may be made 85 in the carrying out of my improved process from what is specifically disclosed herein without departing from the spirit of my invention or the scope of the appended claims. By the term oil as used in the claims, I intend 90 to include the vapor as well as the liquid form, unless the context will not admit of this construction.

What I claim is:

1. Apparatus for heating fluids comprising 95 a chamber, means for admitting a fluid to be heated thereto, injector means in said chamber for admitting the heating fluid whereby to create a stream of said mixed fluids of relatively high velocity, injector 100 means in the path of said stream utilizing the velocity thereof to draw into said stream additional quantities of the fluid to be heated and auxiliary injector means in line with said means last mentioned for admitting additional 105 quantities of heating fluid into said stream, said injector means last mentioned being disposed so as to augment the injector action of said stream.

2. The method of cracking hydrocarbon 110 compounds which consists in injecting into a body of said compounds by means of an injector device a gaseous heat carrier fluid having a temperature in excess of the desired cracking temperature whereby to create a 115 moving stream of the fluid mixture, immediately employing the velocity of the said stream in a further injector device to draw into said stream further quantities of the compounds to be cracked, thereby accomplishing the heating of said compounds to the optimum cracking temperature before substantially any cracking can take place below said optimum temperature.

3. The method of cracking hydrocarbon 125 compounds which consists in introducing said compounds into a confined region, injecting into said region by means of an injector device a gaseous heat carrier fluid having a temperature in excess of the desired 130

cracking temperature whereby to create a moving stream of the fluid mixture, and immediately employing the velocity of said stream in a further injector device to draw into said stream further quantities of the compounds from said region to be cracked.

4. The method of cracking hydrocarbon compounds which consists in first vaporizing said compounds without causing them to undergo any substantial amount of cracking, introducing said vaporized compounds into a confined region, injecting into said region by means of an injector device a gaseous heat carrier fluid having a temperature in excess of the desired cracking temperature whereby to create a moving stream of the fluid mixture, and immediately employing the velocity of said stream in a further injector device to draw into said stream further quantities of the compounds to be cracked.

5. The method of cracking hydrocarbon compounds which consists in introducing said compounds into a confined region, injecting into said region by means of an injector device a gaseous heat carrier fluid having a temperature in excess of the desired cracking temperature whereby to create a moving stream of the fluid mixture, immediately employing the velocity of said stream in a further injector device to draw into said stream further quantities of the compounds to be cracked and assisting the injector action of said stream of the fluid mixture by introducing therein an auxiliary stream of said carrier fluid.

6. In an apparatus for heating fluids, a chamber, means for admitting thereto a fluid to be heated, a plurality of injector nozzles in line with one another such that the stream of fluids issuing from one nozzle operates the succeeding nozzle and serves to draw additional fluid from said chamber therein, and means for admitting a heat carrier fluid to the first of said nozzles and auxiliary injector means for admitting auxiliary streams of heating fluid to said subsequent nozzles.

In testimony whereof I have affixed my signature to this specification.

CHARLES P. TOLMAN.
